UNITED STATES PATENT OFFICE

2,475,381

FEED DEVICE FOR MILLS FOR MILLING GRAIN

John A. Erickson, Jackson, Mich.

Application March 27, 1944, Serial No. 528,246

6 Claims. (Cl. 222—368)

1

This invention relates to improvements in feed devices for mills for milling grain.

The main objects of this invention are:

First, to provide a feed device for a hammer mill or the like which provides a very uniform flow or delivery of the grain to the mill.

Second, to provide a feed device for mills having this feature of providing a uniform flow of the grain to the mill which is not likely to become clogged and is adapted for use in the milling of a wide variety of grains.

Third, to provide a feed device for grinding mills which requires little attention on the part of the operator.

Fourth, to provide a feed device for mills which is well adapted for use in mills designed for the use of individuals as distinguished from custom mills.

Objects relating to details and economies of the invention will appear from the description to follow. The invention is defined and pointed out in the claims.

A preferred embodiment of the invention is illustrated in the accompanying drawing, in which:

Fig. 1 is a fragmentary view of a hammer mill embodying the features of my invention partially in vertical section on line 1—1 of Fig. 2.

Fig. 2 is an enlarged fragmentary view mainly in vertical section on line 2—2 of Fig. 1.

Fig. 3 is a perspective view of the feed wheel.

Fig. 4 is a sectional view on line 4—4 of Figs. 1 and 2.

Fig. 5 is a sectional view on line 5—5 of Figs. 1 and 2.

I have illustrated my invention as embodied in a hammer type mill in which type mills it is highly desirable that the grain to be milled be uniformly fed or delivered to the mill and also it is highly desirable to provide a mill that requires little attention on the part of the user so that the mill may be started and permitted to run for a considerable period of time without specific attention—for example, in the use of farmers or dairymen the mill may be started and permitted to run while the farmer or dairyman is engaged with other work or chores.

In the accompanying drawing, I illustrate only fragments of a hammer mill, the housing being designated by the numeral 1 and having a feed opening 2 in one of its end walls. The shaft 3 is suitably driven and is provided with a series of spiders 4 carrying the pivot rods 5 for the hammers 6. These are conventionally illustrated as is also the screen 7.

2

My feed device comprises a feed cylinder 8 having inner and outer cylindrically curved side wall portions 9 and 10, respectively, and flat parallel end wall portions 11. These end wall portions carry bearings 12 for the feed wheel shaft 13 driven by a suitable train of gears, one of the gears being shown at 14.

The hopper 15 opens to the top of the feed cylinder. Commonly a supply chute is provided from the elevated bin or container for a considerable quantity of grain to be ground, this supply chute delivering into the hopper.

The discharge chute 16 opens to the bottom of the feed chamber and this discharge chute is provided with an inclined bottom 17 joining or merging into the outer cylindrical side wall portion 10 above 18. The chute delivers to the feed opening 2. The bottom wall of the chute has a flat portion 19 at its lower end. It is also provided with a channel 20 which comprises an upwardly tapered portion 21 constituting a throat, the walls of which merge into the cylindrically curved wall portion 10, and a downwardly tapered portion 22, the walls of which merge into the flat delivery portion of the chute bottom. This provides an upwardly tapered discharge throat for the feed cylinder and at the same time for an effective spreading of the grain as it is discharged from the chute into the mill. By reference to Figs. 2 and 5 it will be noted that the bottom wall of the chute is provided with feed guiding surfaces disposed outwardly beyond the opposite sides of the upwardly tapered portion 21 of the channel 20. These oppositely disposed feed guiding surfaces are disposed in substantial alignment with each other when viewed transversely of the chute, and are more nearly flat than is the upwardly tapered channel portion 21 intermediate the same. A considerable portion of the feed that is deposited upon these oppositely disposed surfaces tends to move into such channel portion 21 as the feed slides downwardly over the same. This facilitates an even distribution of the feed across the entire bottom of the upper channel portion 21. The feed flows from the upper channel portion into the downwardly tapered channel portion 22, the relatively tapered side walls of which facilitating an even distribution of the feed onto the flat surface of the chute across the entire width thereof at its lower end.

The feed wheel, in the preferred embodiment illustrated, comprises a pair of vane members 23 having hub portions 24 and outwardly tapered radial vanes 25 integral therewith, these hub portions receiving the non-circular bushings 26 which

are engaged by threaded portions 27 of the shaft 13. It will be noted that the vanes of the two feed wheels are arranged in staggered relation, a partition in the form of a disk 28 being arranged between the vane members.

This arrangement provides a series of pockets 29 which overlap in the feed wheel. The cylindrical walls of the cylinder constitute the outer walls of the pockets and the end walls of the cylinder the outer end walls thereof.

It will be observed that the hopper opens into the feed cylinder so that the ends of the vanes sweep into the bottom of the hopper as the feed wheel rotates and constitute agitators at the bottom of the hopper to prevent clogging.

The vane members are formed of yieldable but substantially rigid material so that they are effective in carrying grain and even portions of cobs, for example, through the feed cylinder and at the same time may yield in the event of a piece of cob, for example, becoming lodged between the discharge throat of the hopper and a vane. The disk 28 is also preferably of flexible material and while it constitutes an effective partition member may yield to prevent wedging of the grain.

The cylindrically curved side walls of the cylinder are a substantial arc so that in all angular positions of rotation of the feed wheel, the vanes close off direct communication between the hopper and the discharge chute. As the feed wheel rotates, the pockets are successively brought into communication with the upwardly tapered recess or channel portion 21 so that the contents of the pockets are gradually discharged into the discharge chute, thereby providing a substantially uniform flow of the grain to the mill. The merging of the walls of this recess into the walls of the cylindrical cylinder member 10 provides for a gradually opening valve-like action for discharging the pockets of the feed wheel, and it will be noted that the recess is of such length that there is at least one pocket in communication therewith at all times.

The forming of the feed wheel of at least two vane members with their vanes in staggered relation results in a more uniform delivery than would result from a feed wheel formed of a single vane member although desirable results can be secured with a single vane member.

I have illustrated and described my invention in an embodiment that has been found by considerable use to be highly practical and satisfactory. I have not attempted to illustrate and describe various adaptations and modifications as I believe this disclosure will enable those skilled in the art to embody or adapt my invention as may be desired.

The structure illustrated is adapted for use in grinding different grains. Different screens 7 may be substituted for securing desired variations in the fineness of the product. This however is well understood in the art.

Having thus described my invention, what I claim as new and desire to secure by Letters Patent, is:

1. In a feed device for mills and the like, the combination of a feed wheel cylinder having opposed cylindrically curved side wall portions of substantial arc, a feed hopper opening to the top of said feed cylinder, a discharge chute opening to the bottom of said feed cylinder, said chute comprising an inclined bottom merging into one cylindrically curved wall portion of said feed cylinder and having a central channel therein

comprising an upwardly tapered upper portion, the walls of which merge into the said one cylindrically curved wall portion and a downwardly tapered portion, said inclined bottom having a substantially flat feed guiding surface, the tapering edges of said downwardly tapered channel portion gradually merging outwardly into said flat surface to permit the feed to flow transversely over the tops of said edges onto said flat surface while flowing longitudinally of said edges to facilitate a uniform feed from the discharge chute, a driven feed wheel rotatably mounted in said feed cylinder and comprising axially aligned vane members each having a plurality of radial outwardly tapered yieldable but substantially rigid vanes, the vanes of the vane members being disposed in staggered relation, and a yieldable disk arranged between said vane members, the arc of said opposed cylindrically curved side wall portions of the feed cylinder being such that in all angular positions of rotation of said feed wheel direct communication between said hopper and chute is cut off by vanes of the feed wheel, the said vanes and disk coacting to provide a plurality of feed pockets successively opening to said hopper and to said discharge chute, said channel acting to provide a gradually opening discharge for the contents of the pockets to the chute, the vanes sweeping into the bottom of the hopper to constitute agitators at the bottom of the feed hopper.

2. In a feed device for mills and the like, the combination of a feed wheel cylinder having opposed cylindrically curved side wall portions of substantial arc, a feed hopper opening to the top of said feed cylinder, a discharge chute opening to the bottom of said feed cylinder, said chute comprising an inclined bottom merging into one cylindrically curved wall portion of said feed cylinder and having a channel therein comprising an upwardly tapered upper portion, the walls of which merge into the said one cylindrically curved wall portion and a downwardly tapered portion, said inclined bottom having a substantially flat feed guiding surface, the tapering edges of said downwardly tapered channel portion gradually merging outwardly into said flat surface to permit the feed to flow transversely over the tops of said edges onto said flat surface while flowing longitudinally of said edges to facilitate a uniform feed from the discharge chute, a driven feed wheel rotatably mounted in said feed cylinder and having a plurality of radial vanes, the arc of said opposed cylindrically curved side wall portions of the feed cylinder being such that in all angular positions of rotation of said feed wheel direct communication between said hopper and chute is cut off by vanes of the feed wheel, the said vanes providing a plurality of feed pockets successively opening to said hopper and to said discharge chute, said channel acting to provide a gradually opening discharge for the contents of the pockets to the chute.

3. In a feed device for mills and the like, the combination of a feed wheel cylinder having parallel end wall portions and opposed cylindrically curved side wall portions of substantial arc, a feed hopper opening to the top of said feed cylinder, a discharge chute opening to the bottom of said feed cylinder, said chute comprising an inclined bottom having a flat delivery portion at its lower end and having a substantially flat feeding guiding surface joining one cylindrically curved wall portion of said feed cylinder and having an upwardly tapered feed guiding channel centrally

disposed in said substantially flat feeding guiding surface and merging into the said cylindrically curved wall portion of the feed cylinder and merging along the opposite tapered edges thereof into said substantially flat feeding guiding surface of said chute bottom below said cylindrically curved wall, and a driven feed wheel rotatably mounted in said feed cylinder and comprising a plurality of vanes, the arc of said opposed cylindrically curved wall portions of the feed cylinder being such that in all angular positions of rotation of said feed wheel direct communication between said hopper and chute is cut off by vanes of the feed wheel, the said vanes providing a plurality of feed pockets successively opening to said hopper and to said feed guiding channel of said discharge chute.

4. In a feed device for mills and the like, the combination of a feed wheel cylinder having opposed cylindrically curved side wall portions, a feed hopper discharging to the top of said feed cylinder, a discharge chute opening to the bottom of said feed cylinder and comprising an inclined bottom joining one of said cylindrically curved wall portions of said feed cylinder and having a downwardly expanding discharge throat the walls of which merge into said one cylindrical wall portion, said inclined bottom having substantially flat feeding guiding surfaces disposed on opposite sides of said throat and merging into said throat and disposed substantially in a common plane, a driven feed wheel rotatably mounted in said feed cylinder and comprising axially aligned vane members each having a plurality of radial vanes, the vanes of the vane members being disposed in staggered relation, and a partition arranged between the vanes of said vane members and coacting with the vanes to provide a plurality of feed pockets successively opening to said hopper and to said recess of said discharge chute, said discharge throat being centrally disposed relative to said partition, said discharge throat being of such dimensions that one or more of said pockets communicates therewith at all times.

5. In a feed device for mills and the like, the combination of a feed wheel cylinder having opposed cylindrically curved side wall portions, a feed hopper discharging to the top of said feed cylinder, a discharge chute opening to the bottom

of said feed cylinder and comprising an inclined bottom and feed guiding side wall members disposed along the opposite side edges of the bottom, said inclined bottom joining one of said cylindrically curved wall portions of said feed cylinder and having feed guiding walls offset from the general plane of the bottom of the chute, the direction of said walls longitudinally along the tops thereof being inclined laterally to the direction of the length of said bottom, said walls being relatively shallow to permit the feed to flow over the tops of the same while flowing longitudinally thereof to facilitate a substantially uniform feed from said chute, and a driven feed wheel rotatably mounted in said feed cylinder delivering to said discharge chute.

6. In a feed device for mills and the like, a discharge chute comprising an inclined bottom and feed guiding side wall members disposed along the opposite side edges of the bottom, said inclined bottom having feed guiding walls offset from the general plane of the bottom, the direction of the lengths of said walls being inclined towards each other and inclined laterally to the direction of the length of the bottom, said walls being relatively shallow to permit the feed to flow over the tops of said walls while flowing longitudinally thereof, to facilitate a substantially uniform feed from said chute.
